E. R. SARGENT,
COFFIN ORNAMENT OR THE LIKE,
APPLICATION FILED JULY 27, 1917.

1,258,147.

Patented Mar. 5, 1918.

Edward R. Sargent, INVENTOR
By Henry P. Chittenden, ATTORNEY

UNITED STATES PATENT OFFICE.

EDWARD R. SARGENT, OF NEW HAVEN, CONNECTICUT, ASSIGNOR TO SARGENT AND COMPANY, OF NEW HAVEN, CONNECTICUT, A CORPORATION OF CONNECTICUT.

COFFIN ORNAMENT OR THE LIKE.

1,258,147.

Specification of Letters Patent.

Patented Mar. 5, 1918.

Application filed July 27, 1917. Serial No. 183,176.

To all whom it may concern:

Be it known that I, EDWARD R. SARGENT, a citizen of the United States, residing in the city and county of New Haven, State 5 of Connecticut, have invented certain new and useful Improvements in Coffin Ornaments or the like, of which the following is a full, clear, and exact description.

This invention relates primarily to a 10 metal cross to be used as a coffin ornament or the like.

One of the main objects of the invention is to provide an improved construction of sheet metal cross, although the invention 15 may also be applied to the construction of other articles.

More particularly, it is aimed to furnish a sheet metal cross which can be made with maximum facility and with a minimum 20 amount of waste material. For this purpose, the cross is composed of two separate sheet metal members fastened together by a novel and meritorious joint or fastening. If desired, a corpus may be readily applied 25 to the completed cross to form a crucifix.

To these and other ends, the invention consists in the novel features and combinations of parts to be hereinafter described and claimed.

30 In the accompanying drawing,

Figure 1 is a front elevation of a cross embodying my improvements.

Fig. 2 is an enlarged rear elevation of the joint between the two members;

35 Figs. 3 and 4 are sections on lines 3—3 and 4—4 of Fig. 2;

Fig. 5 is a fragmentary, perspective view of the upright member; and

40 Figs. 6 and 7 are fragmentary front and rear elevations, respectively, of the transverse or horizontal member.

In making the improved cross, I use an upright sheet metal strip or member 10 and a transverse horizontal sheet metal member 45 or strip 11. Each of these strips is preferably stamped up in the shape of an elongated rectangle, and preferably each of the members 10, 11 is provided with a rearwardly turned flange 12, 13, respectively, 50 extending along the outer edge, thus forming channel members consisting of the flanges 12 or 13 connected by the integral web 10 or 11. Intermediate the ends of the transverse member 11, the same is formed at 55 the front face with a seat 14 for the up-

right member. This seat 14 is relatively shallow and extends transversely across the member 11 from one flanged edge to the other, and at the sides of the recess but within the limits thereof are slots 15, one 60 at each side. The seat 14 can be very readily formed by bending the sheet metal blank in the process of stamping up the horizontal member 11, as will be understood. The upright member 10 extends across the front 65 face of member 11 and lies in the seat 14, and in order to permit the member 10 to lie snugly in the seat, the flange 12 is cut away, as shown at 16, in Fig. 5, so that the rear face of the body portion of member 70 10 may bear tightly against the front face of the seat 14. The flange 12 is not cut away completely across the length of seat 14; as portions 12^a substantially equal in width to the length of slots 15 are left intermediate 75 of the respective cut-out portions 16, and these flange portions 12^a constitute lugs which register with, and pass through, the slots 15 to the rear of the cross where they are bent over and clenched, as shown at 17 80 in Fig. 2, for the purpose of firmly securing the two members 10 and 11 together. When the parts are assembled, the front face of member 10 lies substantially flush with the front face of member 11, as shown more 85 particularly in Fig. 4.

The construction described is a very simple and cheap one, because both members of the cross can be very readily stamped up and there is very little waste of material. 90 The waste of material is negligible as compared to the case where a sheet metal cross is stamped up from a single blank, because in such case a very considerable portion of the material has to be scrapped. If it is desired to make a crucifix, a corpus can be attached in any appropriate manner.

Various changes may be made in the details without departing from the scope of the invention as defined in the claims. For 100 example, it is manifest that if desired the shallow seat may be formed in the upright member instead of the horizontal member, in which case the locking lugs will be formed on the horizontal member. 105

What I claim is:

1. In a cross, intersecting sheet metal members having rearwardly turned integral flanges, one of said members having its flanges notched to form a clearance space in 110

which the other member is seated, and a lug on one of said members passing through the other and fastening them together.

2. In a cross, a pair of intersecting channel members, one of said channel members having its flanges notched to form a clearance space in which the other channel member is seated, said notches being positioned to form an integral lug upon each flange of the first mentioned member, and a slot for receiving said lugs formed in the other channel member, whereby said channel members are secured together.

3. In a cross, a pair of intersecting channel members, one of said channel members having its flanges notched to form a clearance space in which the other channel member is seated, with the face of one channel member contacting with the rear surface of the web of the other channel member, and securing lugs formed integrally upon one channel member and having clenching engagement with the other channel member.

4. In a cross such as described, the combination of intersecting sheet metal members, one of said members having rearwardly turned flanges along the side edges, said flanges cut away at the point where said member intersects the other, and means for fastening the members together.

5. In a sheet metal cross, a sheet metal member having an intermediate seat on the front face thereof, and a second sheet metal member lying flatwise in said seat and secured to said first member.

6. In a cross, a member having a shallow seat extending across the front face thereof, a second member having rearwardly turned side flanges, intersecting said first member and lying in said seat, said flanges cut away so that the body of said second member lies substantially flat in said seat, with the outer face of said second member substantially flush with that of the first member.

7. In a sheet metal cross, a sheet metal member having a transverse seat extending across the same from side to side, said member provided with slots at opposite sides of the seat, and a second sheet metal member having rearwardly turned flanges cut away so that the body of said second member lies in said seat, certain portions of the flanges of the second member extending through said slots.

8. In a sheet metal cross, a sheet metal member having rearwardly turned side flanges and provided with a shallow transverse seat extending across the front face thereof, a second sheet metal member lying in front of the first and also having rearwardly turned side flanges, said last-named flanges cut away at the intersection of the two members, and the body of said second member lying in contact with said seat substantially flush with the body of the first member, and means for fastening the two members together.

In witness whereof, I have hereunto set my hand on the 25th day of July, 1917.

EDWARD R. SARGENT.
